UNITED STATES PATENT OFFICE

WILLIAM W. O'DELL, OF MINNEAPOLIS, MINNESOTA

CHECKER BRICK

Application filed September 25, 1926. Serial No. 137,740.

My invention relates to an improvement in the checker bricks commonly used in enriching chambers or in gas generators in making such gas as carburetted water-gas, oil-gas and the like and briefly comprises a tubular refractory with a wall thinner than commonly employed fire bricks and of short tubular length.

The objects of my invention are, to:

- 10 1. Increase the surface of checker bricks per unit volume of space in the carburetting chambers and oil-cracking chambers of combustible-gas generating sets without increasing the resistance to the passage of gas through said chambers and without decreasing the void space therein.
- 15 2. Increase the heat available without excessive fluctuations in the temperatures of the checker-bricks in gas-making chambers.
- 20 3. Eliminate deposits of carbonaceous material and the resultant stoppage of gas passages in the checker-chambers of gas-making apparatus.
- 25 4. Increase the oil-gasification efficiency in making carburetted water-gas, oil-gas and the like.
- 30 5. Increase the heating surface and contact surface in the carburetting chambers of gas generating apparatus.
- 35 6. Provide a readily adjustable contact medium for contacting moving fluids with solid surfaces in confined chambers affording maximum available solid surface per unit of chamber volume.
- 40 7. Provide checker bricks which can be placed and spaced in checker chambers in a variety of ways without appreciably altering the size of the gas passages through the mass of checker bricks; the surface and volume of checker bricks being the chief variables.

In common practice making oil-gas and in carburetting water-gas or other gas of low calorific value, oil or other carburetting material is introduced, as a spray or mist, into one or more chambers filled with spaced fire-brick which are heated to a predetermined temperature judged to be suitable for gasifying the oil. The temperatures of the surfaces of the checker bricks are carefully controlled pyrometrically. In making oil-gas having

a calorific value of 550 B. t. u. per cubic foot the commonly preferred temperature is 1650 to 1750 degrees Fahrenheit whereas in carburetting water-gas to the same heating value the oil-gas portion of the latter is richer—⁵⁵ (higher in calorific value per cubic foot)—and a suitable temperature is 1350 to 1450 degrees Fahrenheit. In each process the gas is made intermittently and in cycles; the checker bricks are heated during one part of the cycle and carburetting material is introduced during another part of the cycle. Now, the modern tendency to increase the gas-making capacity of such generating apparatus has resulted in short and intensified heating periods, short cycles and increased rate of introduction of the oil or carburetting material. Also, fewer checker bricks are used per unit of volume in the checker chambers than formerly in order to increase the capacity by decreasing the resistance to gas flow. A point has been reached in thus decreasing the length of a cycle in the manufacture of city-gas where the surfaces of the checker bricks are cooled during the gas-making period faster than the heat can be carried from within them to the surface. Likewise during the heating period when the checker bricks are being heated the time allowed is so short that their surfaces are overheated and the interior is ⁶⁰ insufficiently heated. In other words, in present practice in making city-gas the full heat capacity of the checker bricks is not utilized where the surfaces of the checker bricks are cooled during the gas-making period faster than the heat can be carried from within them to the surface. Likewise during the heating period when the checker bricks are being heated the time allowed is so short that their surfaces are overheated and the interior is ⁶⁵ insufficiently heated. In other words, in present practice in making city-gas the full heat capacity of the checker bricks is not utilized because their shape and thickness is not suitably adjusted to meet the prevailing methods of operation. Furthermore, the spacing of these bricks has been increased, for reasons stated and to prevent the excessive accumulation of carbonaceous material and blown over solid fuel, to such an extent that there is commonly insufficient checker-brick surface in the checker chambers to suitably crack the carburetting material. This is clearly shown by excessive gum and resin deposits in gas meters and pipe lines, by the oil-cracking efficiency—(oil-gasification efficiency)—and by the decreased specific gravity of the tar which latter usually contains an increasing percentage of saturated hydrocarbons as the ⁷⁰ oil-gasification efficiency decreases. ⁷⁵

5 Closer spacing of the checker bricks in gas generating apparatus would tend to accomplish what I have accomplished with my bricks but for reasons stated it is not practical to space them closer. The closer these bricks are spaced the more frequently they must be removed and cleaned, and the less the gas-making capacity per unit of time, other things being equal, because of the increased 10 resistance to the flow of gas through the checker chambers. It should be noted that the oil-gasification efficiency decreases rapidly as the deposit or accumulation of carbonaceous matter increases in the mass of checker bricks.

15 I have tried to use thinner checker bricks to accomplish my purpose but found that more labor was required to place them in and remove them from the checker chambers and that difficulty was experienced in maintaining them in position. I find that hollow or tubular bricks, of a different size than fire-bricks which are commonly used for this purpose, are ideally suited for this purpose; their walls should preferably be thinner than two and one-half inches.

20 Figure 1 is a vertical elevation of a carburetted-water-gas set with a portion of the principal shells cut away to show the interior in section, and shows the checker chambers containing tubular checker bricks arranged in flue formation; Figure 2 is a perspective view of a tubular checker-brick with a portion cut away to show the wall in section; 25 Figures 3 and 4 are top views of modified forms of tubular checker-bricks which are suitable for this purpose; Figure 5 is an elevation of a chamber containing spaced checker bricks of the ordinary variety; a portion of the wall is cut away to show the interior in section and to illustrate the two commonly employed methods of spacing and placing checker bricks; Figure 6 is a top view of tubular checker bricks such as shown in Fig. 45 2, arranged in flue formation.

30 In Figure 1, 1 is a water-gas generator containing solid fuel 2 and having steam connections 3 and 4; fuel charging-door 5, air inlet for air-blasting the fuel at 6, offtake connections at 7 and 8 leading to the carburetor. A means for introducing carburetted material into carburetor 9 is shown at 10. The carburetor is connected to the superheater 11 and each of these two chambers contain a 35 mass of checker bricks as shown at 12 and 13. Offtakes are provided in the superheater for waste blast-gas and carburetted gas respectively at 14 and 15. The secondary air inlet to carburetor is shown at 16. The superheater stack-cap is shown at 23.

40 In Figure 2 the checker-brick substance shown at 17 is substantially the wall of a very short tube or conduit the interior of which is shown at 19. A portion of the wall is 45 shown in section at 18.

In Figures 3 and 4, employing the same system of numbering, as in Fig. 2, the shape of the tubular wall is shown for modified forms of tubular checker-bricks.

45 In Figure 5 shell 20 contains ordinary fire 70 bricks—(checker bricks)—spaced in flue formation at 21, and in staggered formation at 22.

50 In Figure 6 one method is shown of spacing tubular checker bricks which are substantially elliptical in horizontal cross sections. The checker bricks shown have flat parallel sides and the ends, as shown, form a semi-circle. The same system of numbering is used as in the previous figures.

55 The outside maximum length of the checker bricks shown in Figures 2 and 6 is substantially equal to twice the inside width plus twice the wall thickness. The sizes of my tubular checker bricks are not limited to any fixed values. However, I find that for bricks having a definite wall thickness there are preferred sizes for different preferred spacing. Thus with a tubular brick as shown in Figures 2 and 6 having a wall thickness of 60 one and one-half inches the preferred dimensions—length and width—are substantially 90 as follows:

	Length, outside dimensions	Width, outside	Minimum inside diameter	95
For 2 inch spacing	7 inches	5 inches	2 inches	
For 3 inch spacing	9 inches	6 inches	3 inches	
For 4 inch spacing	11 inches	7 inches	4 inches	
For 5 inch spacing	13 inches	8 inches	5 inches	
For 6 inch spacing	15 inches	9 inches	6 inches	

65 These bricks have two parallel flat sides and the outside length is substantially equal to twice the inside width plus twice the wall thickness.

70 In making tubular checker bricks with a minimum inside diameter of four inches or more, or even with some of the smaller sizes, it may be desirable to provide a wall thicker or thinner than one and one-half inches, in which case the preferred size of the bricks is somewhat different with respect to length and width, which dimensions should be increased or decreased as the wall thickness is increased or decreased, by an amount equal to twice the increment, from the values given above for preferred sizes. For example, the 75 preferred length and width of a tubular checker brick having a two-inch wall, for three inch spacing are respectively 10 inches and 7 inches with an inside tubular diameter of 3 inches. The height—tubular length—can be any dimension from a few inches to a foot or even more. The use to which the bricks are put and the effect desired have bearing upon the selection of a preferred height. For use in gas-generating apparatus 80 it is convenient to make these bricks about four and one-half inches high, equal to the width of standard fire bricks. One advantage in making them this size or a multiple thereof is: they can be used conveniently 85

in conjunction with fire bricks when thus made.

It is obvious that my checker bricks, as shown in Figures 2 and 6 can be arranged in flue formation or in staggered formation similarly as the commonly employed fire bricks. It will be seen that by variously arranging the former, or by spacing them widthwise a distance apart unequal to the internal tubular diameter, effects are produced which it is difficult if not impossible to obtain with fire bricks. In Figure 6 the bricks are arranged contacting one another at their ends but this is not necessary; they may be spaced a predetermined distance apart endwise as desired. Because of the shape of my bricks they can be arranged in this manner without weakening the whole structure—(mass of arranged checker bricks)—whereas greater consideration must be given to this point when using ordinary fire bricks which are approximately $2\frac{1}{2}$ by $4\frac{1}{2}$ by 9 inches in size. My bricks are particularly well adapted therefore, for use in checkering flash type waste-heat-boilers in which steam is generated and superheated by the heat intermittently stored in massed checker-bricks. In such apparatus a large part of the transfer of heat energy is performed in particular portions of the boiler and in such portions it is obviously desirable to increase the heat storage-capacity by a closer spacing of the checker bricks.

With ordinary fire bricks spaced three inches apart with ends contacting as in common practice the percentage of void space equals $(3 \times 100) \div (2.5 + 3)$ or 54.5. With tubular checker bricks as shown in Figures 2 and 6 spaced three inches apart and end to end the void space is approximately 63.4 per cent. The difference 63.4—54.5 is 8.9 and the latter figure represents a percentage increase of 16.3 in the void space. The surface exposed with the fire bricks spaced 3 inches apart is approximately 820 square inches per cubic foot of space in the checker chamber whereas with the tubular checker bricks as above the surface exposed is approximately 980 square inches per cubic foot of chamber space. The difference, 980—820 or 160 represents an increase of 19.5 per cent in the surface exposed, upon changing from fire bricks to the tubular checker bricks shown in Figures 2 and 6.

Obviously the volume of solid refractory per volume of chamber space is less with the tubular checker bricks than with common fire bricks. It will be noted that with short heating and cooling cycles the temperature in the middle of a thick brick does not fluctuate appreciably if at all hence the actual heat-carrying capacity of my brick under these conditions is not diminished by this decrease in volume of refractory. Hence in making oil-gas or carburetted water-gas it is possible,

by the use of tubular checker bricks, to increase the gas-making capacity, oil-cracking efficiency, the volume of void space in the mass of checker bricks and the total amount of checker-brick surface per unit of chamber volume and to decrease the difficulty experienced by stoppages in the mass of checker bricks.

It will also be noted that a greater percentage of the exposed surface is active surface with tubular checker bricks than with fire bricks.

The preferred shape of my checker brick is substantially as shown in Figures 2 and 6; the sides being flat and parallel and the ends being circular. This form has advantages over bricks which are truly elliptical in cross section for reasons which are apparent upon arranging them in a checker chamber. However it is recognized that tubular bricks having a cross section which is substantially rectangular, octagonal, hexagonal, circular, elliptical or the like is superior to common fire bricks for checkering purposes. Believing that the use of short tubular checker bricks is new in gas making processes the claims are written with the intent to broadly cover this point.

Attention is called to the fact that in times past the length of the operating cycle, in making carburetted water-gas and the like, was twenty-five to forty-five minutes; about half of this time being used for heating the checker bricks and the remainder for the gas-making period during which time the heat stored in the checker bricks is utilized. Under these conditions sufficient time was allowed for the full utilization of the heat capacity of fire bricks or similar solid checker bricks. At present the length of a complete cycle is five to six minutes, consisting in a two minute heating period and a three to four minute gas-making period, the carburetting material being added during two to three minutes of the gas-making period. During the latter period the oil is injected so rapidly that the surfaces of the ordinary checker bricks become cooled below a satisfactory gas-making temperature even though considerable heat is still stored in these bricks. The essential requirement in this process is that there be plenty of exposed checker-brick surface heated to a gas-making temperature. The desirability of increasing the amount of checker-brick surface in gas-making checker chambers is largely the result of the recent changes in the operating cycle and the increased rate of making gas. The need for this increased surface area is generally recognized among gas engineers who also understand that ordinary fire bricks can not be thus arranged without causing deleterious effects.

In common practice the blast-gas used for heating the checker bricks in making carburetted water-gas varies in composition dur-

ing the brief blasting period. At the start it is composed chiefly of nitrogen and carbon dioxide with very little combustible matter, becoming richer as the generator blasting is continued, finally reaching a maximum heating value of 110 to 135 B. t. u. per cubic foot at the end of the blast period. The flame temperature in the checker chambers is too low to impart sufficient heat to thick checker 10 bricks of relatively small surface-volume ratio in the usual brief blasting period. I find that a greater amount of heat energy can be transferred per unit of time during the different portions of the operating cycle when tubular bricks are used having a surface-volume 15 ratio greater than that of fire bricks.

The substance of which my checker bricks are composed may be any solid material capable of being shaped as described. Obviously 20 they must be made of refractory material when intended to withstand high temperatures such as prevail in the gas-making chambers of carburetted water-gas sets or oil-gas sets. The term "refractory material" as used 25 here includes metals.

My checker-brick when spaced and arranged in formation in a checker chamber for use in heat exchange are in reticular formation; by reticular formation I mean the 30 structure is a net work of checker-bricks. This differentiates the structure from recuperators and similar structures in which hollow tile are commonly placed end to end making continuous conduits and not a reticular or 35 network structure. The fact that my bricks are arranged in a net-like structure does not completely differentiate my structure from that of a recuperator through which a gas may pass in one direction within tubular channels 40 and in an opposite direction on the outer side of said channels. By reticular formation I refer to a particular network of checker-bricks, namely, that in which the bricks are spaced and arranged in a network formation 45 comprising a plurality of superposed courses. The bricks are spaced and arranged in the different courses. They are spaced and arranged in such a manner that the bricks of one course 50 are not tubularly continuous with those of adjacent courses. Thus the bricks as arranged in my structure are tubularly discontinuous whereas in recuperators they are arranged to be tubularly continuous. In other words the bricks are so arranged in my structure that 55 their ends (tube ends) do not symmetrically contact one another. A fluid passing through this structure is not confined to either the inner or outer side of the bricks but may contact the inner side of some of the bricks and 60 the outer side of others.

I claim:

1. In a checker-brick device comprising a plurality of spaced and arranged checker-bricks, said bricks being substantially short, 65 flattened, refractory, open-end tubes having

thin walls of substantially uniform thickness and arranged in reticular formation in substantially parallel spaced relation to form a plurality of superposed layers, each superposed layer having its bricks angularly disposed with relation to the bricks of adjacent upper and lower layers. 70

2. In a checker-brick device comprising a plurality of spaced and arranged checker-bricks, said bricks being substantially short, 75 flattened, refractory tubes having thin walls of substantially uniform thickness and arranged in reticular formation in substantially parallel spaced relation to form a plurality of superposed layers, each superposed layer having its bricks angularly disposed with relation to the bricks of adjacent upper and lower layers; said layers collectively forming a plurality of parallel tubes having discontinuous walls and a plurality of substantially 80 parallel channels the walls of which are discontinuous comprising the outer walls of said bricks. 85

3. In a checker-brick device comprising a plurality of tubular, spaced and arranged checker-bricks, said bricks being substantially short, 90 flattened, refractory tubes having thin walls and arranged in reticular formation in substantially parallel spaced relation to form a plurality of superposed layers, each layer 95 having its bricks angularly disposed and tubularly discontinuous with relation to the bricks of adjacent upper and lower layers.

4. In a checker-brick device comprising a plurality of tubular, spaced and arranged checker-bricks, said bricks being substantially short, 100 flattened, refractory tubes having thin walls and arranged in reticular formation in substantially parallel spaced relation to form a plurality of superposed layers, each layer 105 having its bricks angularly disposed and tubularly discontinuous with relation to the bricks of adjacent upper and lower layers; substantially each of said arranged bricks in said superposed layers being supported by and contacting a portion of the walls of four of the bricks in the next lower layer. 110

5. In a checker-brick device comprising a plurality of spaced and arranged tubular checker-bricks, said bricks being substantially short, 115 flattened, refractory tubes, having rounded end-walls and substantially flat side-walls and arranged with their tube-axes substantially vertical in reticular formation in substantially parallel spaced rows to form a plurality of superposed layers, each of said superposed layers having its rows angularly disposed with relation to those of adjacent upper and lower layers and spaced a distance substantially equal to the short inside diameter of said refractory tubes, the bricks of each layer being tubularly discontinuous with those of adjacent layers. 125

6. In a checker-brick device comprising a plurality of spaced and arranged tubular 130

5 checker-bricks, said bricks being substantially short, flattened refractory tubes, having a wall thickness "x" and an inside short-diameter "y", an outside long-diameter substantially equal to $(2y+2x)$, an outside short-diameter substantially equal to $(2x+y)$ and arranged in reticular formation in substantially parallel spaced rows to form a plurality of superposed layers, substantially each layer having its rows angularly disposed with relation to those of adjacent upper and lower layers.

10 7. In a checker-brick device comprising a plurality of spaced and arranged tubular checker-bricks, said bricks being substantially short, flattened, open, tubes having a wall thickness "x", an inside short-diameter "y", an outside long-diameter substantially equal to $(2y+2x)$, and an outside short-diameter substantially equal to $(2x+y)$, arranged vertically tubularly in substantially reticulated formation comprising a plurality of superposed courses.
